Inventor:

UNITED STATES PATENT OFFICE.

HÅKAN OLSON, OF SOPERVILLE, ILLINOIS.

HORSESHOE-CALK.

SPECIFICATION forming part of Letters Patent No. 599,350, dated February 22, 1898.

Application filed May 23, 1896. Serial No. 592,720. (No model.)

To all whom it may concern:

Be it known that I, HÅKAN OLSON, a citizen of the United States, and a resident of Soperville, in the county of Knox and State 5 of Illinois, have invented certain new and useful Improvements in Horseshoe-Calks, of which the following is a specification.

My invention relates to horseshoe-calks wherein an iron body is fitted with a steel 10 core; and the object of my invention is to produce an improved calk which may be readily and securely attached to the shoe and which may be easily and inexpensively manufactured, as will hereinafter appear.

15 In the accompanying drawings, Figure 1 is a perspective view of the under side of a horseshoe fitted upon one side with my improved toe, nail, and heel calks; Fig. 2, a plate-iron blank having slotted holes punched out there- 20 in in its middle longitudinal line to receive steel bearing-plate spurs; Fig. 3, a plan of a double-headed set of blanks fitted and folded together ready to be cut up in toe-calk sections; Fig. 4, a transverse section in line xx 25 of Fig. 3; Fig. 5, a modification of a single-headed set of blanks folded together, each steel-core blank having double spurs for fastening to the shoe; Fig. 6, a perspective view of the calk ready to be fitted on the shoe; 30 Fig. 7, a section through the calk and shoe in line $W W$ of Fig. 1; Fig. 8, a plan of a single-headed set of heel-calk blanks before being cut; Fig. 9, a section in line $y y$ of Fig. 8; Fig. 10, a plan of one of the core and spur 35 plates, and Fig. 11 a perspective view of a finished heel-calk made from folded plates.

The horseshoe A may be of any approved pattern or construction and is provided on its under side with the usual nail-groove or ful- 40 lering a and oblong nail-holes b and also with transverse oblong recesses or holes c to receive the spur of the heel-calks and with a similar recess or recesses d to receive the spur or spurs of the toe-calk, as will hereinafter 45 appear.

The wrought-iron socket portion B of the toe-calk C differs from others heretofore employed in the shape, material, and method of manufacture and union with the steel core- 50 plate, which is substantially as follows: A rolled plate-iron blank f is made slightly ta-

pering or thinned down from its middle longitudinal line to its side edges and has rectangular slots f' punched through the said plate on said longitudinal line at suitable intervals 55 to receive spurs g of equal length and width which project from the side edge of an otherwise rectangular plate of steel g' , which form the core-plate D of the toe-calk. The plate-iron blank f is first rolled or otherwise folded 60 into a U form, closely enveloping the steel-plate blank g' , the spurs fitting snugly and passing through the slots f' therein, after which the plates are rolled solidly together when heated to a welding heat, then cut in 65 sections of the proper length to form toe-calks and bent to conform to the toe of the horseshoe, as shown detached therefrom in Fig. 6, and as attached to the said shoe, as shown in Figs. 1 and 7 of the drawings. The 70 last named, Fig. 7, shows the mode of attachment, which consists of heating the spur or the whole of the toe-calk to a welding heat and then passing said spur through the recess or hole d in the toe of the horseshoe 75 and welding it thereon. Fig. 5 shows blank bars before they are cut and bent to form separate calks and have two spurs upon the steel core, one upon each end of the calk, to hold the latter more securely upon the shoe. 80 The toe-calk C, consisting of the socket portion B and the core-plate D, may be first heated sufficiently and cut from the blank bar and then raised to a welding heat and struck up solidly, welded together, as shown 85 in Fig. 6, and then welded by a second process or blow to the toe of the shoe. The mode of fastening to the shoe, however, is immaterial to this invention.

The preferred method of forming the toe- 90 calk is to provide a double plate-iron blank f for the socket portion of the toe-calk B, as shown in Figs. 3 and 4, in a manner similar to that above described for the single socket-plate and then cut the rolled compound bar 95 into toe-calk sections in the lines 1, 2, 3, 4, 5, 6, 7, 8 by any suitable means.

The heel-calk E, as shown in section in Fig. 9 and in perspective in Fig. 11, is made in a manner similar to that described for the toe- 100 calk, only that a single plate h forms the socket-bar E' and is punched out to receive

wedge-spurs F, which are passed through the said apertures, and the single plate h is folded or rolled down over the said spurs, as shown in Fig. 8, and then cut into separate heel-calks, 5 the core and body being welded together and the body being finally finished and made to envelop completely the core, as shown in Fig. 11, by a drop-forgé, hammer, or dies when the metal is at a welding heat. The mode of at- 10 taching the heel-calks of this pattern to the heel of the shoe is well known, the point of the spur F being hammered into the holes c in the heels of the shoe when sufficiently hot to weld the pieces together.

15 I claim as my invention and desire to secure by Letters Patent—

1. As an improved article of manufacture, a steel plate or web having channeled bars of wrought-iron folded upon and fitted to the 20 opposite longitudinal edges thereof by spurs upon the steel plate which project through holes in the said wrought-iron bars and adapt-

ed to be cut in sections to form horseshoe-calks, substantially as described.

2. As an article of manufacture, a horse- 25 shoe-calk consisting of a socket or jacket made of rolled plate-iron made U-shaped and having a series of apertures in the fold thereof, and a plate of steel having a corresponding series of spurs to fit said aperture and held 30 between the opposite sides or leaves of said iron plate, substantially as described.

3. A heel-calk, made of a wrought-iron channel-bar having a series of perforations fitted with a spur core-plate cut in sections and 35 swaged or forged at its cut ends to close around said core-plate, substantially as described.

In testimony whereof I have hereunto set my hand in presence of two subscribing witnesses.

HAKAN OLSON.
